UNITED STATES PATENT OFFICE.

WILLIAM A. FORCE, OF NEW YORK, N. Y.

DESIGN FOR A RUBBER CUSHION.

43,499.

Specification for Design.

Patented Feb. 4, 1913.

Application filed March 27, 1912. Serial No. 686,624. Term of patent 7 years.

To all whom it may concern:

Be it known that I, WILLIAM A. FORCE, a citizen of the United States, residing in the borough of Brooklyn, city of New York, county of Kings, and State of New York, have invented a new, original, and ornamental Design for Rubber Cushions, of which the following is a specification, reference being had to the accompanying drawing, forming part thereof.

Figure 1 is a plan view of a rubber cushion showing my new design, and Fig. 2 is an edge view of the same.

I claim:—

The ornamental design for a rubber cushion, as shown.

WILLIAM A. FORCE.

Witnesses:

ROBT. B. KILLGORE,
A. J. MANFRED.
